US00D912157S

(12) **United States Design Patent** (10) **Patent No.:** **US D912,157 S**
Hama et al. (45) **Date of Patent:** **** Mar. 2, 2021**

(54) **PLAYING SURFACE FOR SPINNING TOP
TOY**

(71) Applicant: **TOMY COMPANY, LTD.**, Tokyo (JP)

(72) Inventors: **Hiroyuki Hama**, Tokyo (JP); **Douglas Arthur Schultheis**, Cumberland, RI (US)

(73) Assignee: **TOMY COMPANY, LTD.**, Tokyo (JP)

(**) Term: **15 Years**

(21) Appl. No.: **29/721,113**

(22) Filed: **Jan. 17, 2020**

(51) LOC (13) Cl. **21-01**

(52) U.S. Cl.

USPC **D21/338; D21/461**

(58) **Field of Classification Search**

USPC ..... D21/334, 336-342, 355-359, 365, 318, D21/397, 312, 314, 320, 362, 366, 367, D21/385, 455, 456, 460, 461, 484, D21/491-501, 561, 564; 273/242, 273/244-247, 259, 277, 287, 317.3, 273/108.1, 108.5, 118 D, 236-240, 283, 273/309, 441, 461, 108.2, 108.3, 113, 273/115, 116, 241, 280, 282.1, 282.2, 273/282.3, 289, 148 R, 440, 444, 450, 273/453, 459, 109, 110, 108, 456, 443; D6/406.1, 406.3, 406.4, 406.6; D19/86, D19/92, 95, 87, 113, 75, 77, 78, 80; 108/14, 62, 43, 67; 434/416, 247, 248, 434/251, 408, 413, 145, 430; 446/82, 446/168, 236, 256, 257, 259, 262, 263, 446/491, 233; D7/538-550.1, 552.2, D7/553.1-553.8, 554.1-554.4, 558, D7/584-588, 601, 602, 359, 354, 356; D9/737, 756, 758-761, 414, 424-433, D9/456, 499; D30/121, 129-133; D11/143, 144, 152, 153, 155, 156, 164; 47/65, 65.5, 65.6, 66.7, 71, 73-75, 39; 473/569, 570; 463/69

(57) CLAIM

The ornamental design for a playing surface for spinning top toy, as shown and described.

DESCRIPTION

FIG. 1 is a front view of the playing surface for spinning top toy;

FIG. 2 is a left-side view thereof; and

FIG. 3 is a rear view thereof;

FIG. 4 is a right-side view thereof;

FIG. 5 is a top plan view thereof;

FIG. 6 is a bottom plan view thereof;

FIG. 7 is a front, left-side, top perspective view thereof;

FIG. 8 is a rear, right-side, bottom perspective view thereof;

FIG. 9 is a front, left-side, top disassembled perspective view, showing the playing surface separated into a hook, two upper fasteners, four lower fasteners, two screws, two covers, two bases, and two legs;

FIG. 10 is a rear, right-side, bottom disassembled perspective view showing the playing surface separated into the hook, the two upper fasteners, the four lower fasteners, the two screws, the two covers, the two bases, and the two legs;

FIG. 11 is a cross-sectional view taken along line 11-11 in FIG. 5;

FIG. 12 is a cross-sectional view taken along line 12-12 in FIG. 5;

FIG. 13 is a cross-sectional view taken along line 13-13 in FIG. 5;

FIG. 14 is a cross-sectional view taken along line 14-14 in FIG. 5;

FIG. 15 is a perspective view of the hook;

FIG. 16 is another perspective view of the hook;

FIG. 17 is a perspective view of one of the upper fasteners;

FIG. 18 is another perspective view of one of the upper fasteners;

FIG. 19 is a perspective view of one of the lower fasteners;

FIG. 20 is another perspective view of one of the lower fasteners;

FIG. 21 is a perspective view of one of the screws;

FIG. 22 is another perspective view of one of the screws;

FIG. 23 is a perspective view of one of the legs; and,

FIG. 24 is another perspective view of one of the legs.
